UNITED STATES PATENT OFFICE.

GEORGE MOORE, OF MONROE, WASHINGTON.

LOGGING DEVICE.

SPECIFICATION forming part of Letters Patent No. 751,322, dated February 2, 1904.

Application filed September 23, 1903. Serial No. 174,316. (No model.)

To all whom it may concern:

Be it known that I, GEORGE MOORE, a citizen of the United States, and a resident of Monroe, in the county of Snohomish and State 5 of Washington, have invented a new and Improved Logging Device, of which the following is a full, clear, and exact description.

The object of the invention is to provide a new and improved logging device more especially designed for running logs down steep grades under perfect control of the operator without danger of injuring the logs.

The invention consists of novel features and parts and combinations of the same, as will be 15 more fully described hereinafter and then pointed out in the claims.

A practical embodiment of the invention is represented in the accompanying drawings, forming a part of this specification, in which 20 similar characters of reference indicate corresponding parts in all the views.

Figure 1 is a perspective view of the improvement as applied. Fig. 2 is an enlarged side elevation of the brake mechanism for the 25 holdback-cable. Fig. 3 is an end view of the same. Fig. 4 is a perspective view of the connection of the cables with the logs. Fig. 5 is an enlarged perspective view of the clamp for the holdback-cable, and Fig. 6 is a perspective 30 view of the coupling for connecting the ends of the cables with each other.

In transporting logs down a mountain side to the nearest watercourse it has heretofore been the practice to either carry the logs on 35 cars traveling over a circuitous railroad-track or to run the logs down a steep chute or skid-road sometimes several miles in length. The building and maintenance of a circuitous railroad is very expensive, and in sending the logs 40 down a steep chute they gain such momentum, especially in wet weather when the chute is slippery, that the logs dash one into the other or strike the bottom of the watercourse with such force that they are smashed to 45 pieces or otherwise injured. The logs on striking the bed of the watercourse are also liable to pick up stones injurious to the saw in the mill.

With the improvement presently to be de-

scribed in detail the logs are sent down the 50 steepest parts of a chute or skid-road under perfect control of the operator and without danger of the logs being injured by striking one the other or dashing with great velocity into the watercourse.

For the purpose mentioned the log or a plurality of coupled logs A A (see Figs. 1 and 4) are connected with a pull-cable B and a hold-back-cable C, of which the pull-cable B extends in a chute or skid-road D and leads to 60 the drum E (see Fig. 1) of a donkey-engine located at the foot of the chute or skid-road D, preferably adjacent to the watercourse. The holdback-cable C extends from the second 65 drum E' of the donkey-engine to and around the gypsy-drum G' of a brake mechanism G and then extends upward to one side of the chute or skid-road D to the end or landing thereof. At this point the holdback-cable C passes around a large sheave or a series of 70 flanged rollers H, attached to a frame set on the ground or fastened to a stump or other support, and the end of the holdback-cable then connects with the rear log or logs A. In case the skid-road D has bends then suitable 75 guide-pulleys are provided at the bends for guiding the cables.

As shown in Fig. 4, the holdback-cable C is provided at its terminal with a link C', adapted to hook onto the hook I' of a safety-grip I, attached to a log A in the usual manner, and the said cable, adjacent to the rear end of the rearmost log, is engaged by a clamp J, held on a tail-grip K, attached to the rear end of the rearmost log. The clamp J preferably consists of members J' and J², pivotally connected with each other and of which the member J' is bent into U shape, and the member J² extends into the member J' to clamp the cable at the middle portion of the 90 member J', as will be readily understood by reference to Fig. 5.

The upper end of the pull-cable B is provided with links B' and B², of which the link B² hooks onto the hook L' of a head-grip L, 95 connected with the forward end of the lowermost log A, as plainly indicated in Fig. 4. If several logs are sent down at a time, then

the said logs are coupled together by suitable grips or couplers N, as indicated in Fig. 4.

The brake mechanism G, previously mentioned and illustrated in detail in Figs. 2 and 3, is arranged as follows: The gypsy-drum G' is secured on a shaft G², journaled in suitable bearings on a frame G³, and on the said shaft G² is secured a brake-wheel G⁴, engaged at opposite sides by brake-blocks O and O', attached to frames P and P', mounted to slide on the frame G³, so that when the frames are moved toward each other the brake-blocks O and O' firmly brake the brake-wheel G⁴. In order to give this movement to the frames P and 15 P', the frame P' is provided with a transverse bar P², through which extends a rod R, having one end threaded for a hand-wheel R' to screw on and abut against the cross-piece P². The other end of the rod R is pivotally connected with an arm R², secured on a shaft R³, journaled in the upper end of the frame P, and the said shaft R³ is provided with upwardly-extending arms R⁴, connected by links R⁵ with the upper end of the frame P'. By 20 screwing up the hand-wheel R' on the threaded end of the rod R the latter is caused to move from the right to the left, so that a swinging motion is given to the arm R² to turn the shaft R³, which by the arms R⁴ and links R⁵ pulls 25 on the frame P' to draw the latter toward the frame P, thus causing the brake-blocks O and O' to firmly engage the peripheral face of the brake-wheel G⁴ to brake the same, and consequently the shaft G² and the gypsy-drum 30 G'. On turning the hand-wheel R' in an opposite direction the brake-blocks O and O' correspondingly release the brake-wheel G⁴.

The device is used as follows: At the landing or the upper end of the chute or skid-road 35 40 D the ends of the cables B and C are connected with the logs, as previously described, and then a signal is given in any suitable manner to the engineer in charge of the donkey-engine to start the drum E for winding up the pull-cable B and for allowing the cable C to unwind from the drum E'. When this takes place, the pull-cable B pulls the logs on the skid-road from the landing, and when the logs pass down a steep portion of the chute or 45 skid-road then the operator in charge of the hand-wheel R' manipulates the latter to brake the gypsy-drum G', so that the holdback-cable C prevents the logs from traveling too fast down the steep portion of the skid-road—that 50 is, the holdback-cable holds the logs back for the latter to travel at a desired rate of speed when traveling down the steepest portion of the skid-road. When the logs again come to a level portion, or even an upgrade in the 55 60 skid-road, then the operator in charge of the brake mechanism releases the grip on the brake-wheel G⁴ to permit the pull-cable B to easily pull the logs along the level or upgrade portion until the logs again pass to a steep 65 portion in the road, at which time the brake

mechanism again is set in action and the above-described operation is repeated until the logs have safely reached the lower end of the skid-road adjacent to the donkey-engine brake mechanism located near the watercourse. The 70 grips I and K for the pull-back cable C are now disconnected from the logs and also the grip L for the pull-cable B, and then the end of the latter is connected with the rear end of the logs and the donkey-engine is started 75 to wind up the cable B on the drum E for the cable to push the logs down into the watercourse. When this has been done, the ends of the cables C and B are connected together by their links B', B², and C', as illustrated in 80 Fig. 6, and then the donkey-engine is reversed for the drum E' to wind up the holdback-cable C and for the drum E' to unwind the pull-cable B, so that the coupled ends of the cables B and C travel up the chute or skid-road back 85 to the landing, at which point the cables are uncoupled and connected to another set of logs in the manner above described.

Having thus described my invention, I claim as new and desire to secure by Letters Patent— 90

1. A logging device provided with a pull-cable arranged for connection with a log, for pulling the latter, and a holdback-cable arranged for connection with the log and for holding the log back, and a brake mechanism 95 for the holdback-cable, as set forth.

2. A logging device provided with a pull-cable arranged for connection with a log, for pulling the latter, a holdback-cable arranged for connection with the log for holding the 100 log back, means for winding and unwinding the said cables, and a brake mechanism for the holdback-cable, as set forth.

3. A logging device comprising a pull-cable for connection with a log at the forward end, 105 a holdback-cable for connection with the log at the rear end, drums for winding up one of the cables while unwinding the other, a guide for the holdback-cable, located at the starting-point for the logs, and a brake mechanism 110 for the said holdback-cable, as set forth.

4. A logging device for moving logs over a log-chute, comprising a pull-cable, a drum for winding up and unwinding one end of the said cable, a head-grip for connecting the other end of the cable with the forward end of the log, a holdback-cable, a drum for winding and unwinding one end of the said holdback-cable, a tail-grip connected with the other end of the holdback-cable, for connection with the rear end of the log, a guide for the said holdback-cable, located at the starting-point of the road, and a brake mechanism for the said holdback-cable, as set forth. 115 120

5. A logging device for moving logs over a log-chute, comprising a pull-cable for connection with a log at the forward end, a holdback-cable for connection with a log at the rear end, drums for winding up one of the cables while unwinding the other, the drums 125 130

being located adjacent to the lower end of the chute, and a brake mechanism for the hold-back-cable, including a brake-wheel on the shaft of the holdback-cable drum, and brake-blocks for engaging the brake-wheel, as set forth.

6. A logging device provided with a hold-back-cable, a tail-grip carrying a clamp, for engaging the said holdback-cable, and a safety-

grip connected with the terminal of the said holdback-cable, as set forth.

In testimony whereof I have signed my name to this specification in the presence of two subscribing witnesses.

GEORGE MOORE.
